UNITED STATES PATENT OFFICE

1,987,115

BUILDING CONSTRUCTION

Guy F. Kotrbaty, Laurelton, N. Y., assignor to
 Ferrocon Corporation, New York, N. Y., a corporation of Delaware

Original application January 16, 1931, Serial No.
 509,237. Divided and this application December
 30, 1933, Serial No. 704,726

14 Claims. (Cl. 72—1)

This invention relates to improvements in methods and means for joining self-supporting building construction units, as set forth in my application Serial No. 509,237 for Building constructions, filed January 16, 1931, and allowed November 3, 1933, Patent No. 1,968,045, July 31, 1934 of which this application is a division.

The present invention will be described with particular reference to the use of preformed self-supporting construction or grid units which are so constituted and arranged as to allow a plurality of them to be readily associated in any desired type of structure and provided with wall, floor and roof joints of various kinds.

Desirable economies in construction by the use of the improved joints of the present invention will be set forth more in detail in the accompanying specification, reference being had to the drawings, in which like numerals refer to similar parts throughout the several views, and in which

Figure 1 is a horizontal cross section of an improved construction member adapted for walls;

Figure 2 is an elevation, partly in section, of an assembly of elements shown in Figure 1, including a corner connecting member;

Figure 3 is a vertical cross section taken through a section of a building at the junction of the foundation and first floor;

Figure 4 is a vertical section taken through the aligned partitions in a house, together with associated floor assembly;

Figure 5 is a view similar to Figure 3 showing preferred connections between upper floors and outer wall;

Figure 6 is a detail of a base connecting member for connection of main house wall to foundation wall above grade line;

Figure 7 is a detail of a base mould and structural member;

Figure 8 is a detail, partly in section, of a wall cap grid member and floor grid supporting member;

Figure 9 is a detail of a channel member adapted to receive the wall grid and serve as a support therefor;

Figure 10 is an elevation, partly in section, of a wall tie member adapted to be interposed between two floors;

Figure 11 is a vertical cross section through a roof and wall junction, and

Figure 12 is a vertical cross section through a ridge portion.

Referring now to the drawings, the improved construction member shown in Figures 1 and 2, and designated generally by the numeral 10, com-

prises a pair of opposed wall members 11 of sheet metal, which may be solid or of any suitable foraminous metallic construction. These members may be provided with a plurality of stiffening members 13, which as shown are indicated as integral horizontal stiffening grids. However, it will of course be appreciated that the stiffening members may be vertically disposed or they may comprise associated members such as stiffening rods or battens, which may be secured to either or both sides of the members as by soldering, brazing, or welding, and such members may be opposed on either side of the members 11 and 12 to provide an increased stiffening effect. If desired, foraminous metal of the expanded metal lath type may be used, and a desirable stiffening imparted thereto by weaving or otherwise associating stiffening wires therethrough in any desired manner.

The sections 14 disposed between the stiffening members 13 may be of solid metal as above indicated, or may comprise expanded lath portions, or perforated sections.

The side members are connected together by means of combination end sections and keyways, 25 as shown in Figure 2 and designated generally as 15, which usually comprise a central cylindrical portion 16 having an aperture 17 and oppositely disposed flanges 18, which flanges are continued at 19 to form re-entrant sections, which, in turn, 30 are reversely bent to form clip members 20 adapted to be secured in locking engagement with the ends 12 of members 11.

The metallic construction and method of bonding of walls and floors, now about to be 35 described, permits a pronounced flexibility in construction due to the fact that by varying the configuration of the grid members any desired metallic structure may be made use of, and this latter suitably augmented by the advantage and 40 incorporation in the metallic structural unit of a desirable structural plastic embedment.

Referring now to Figs. 3 to 12, inclusive, the improved building joint constructions of the present invention will be described in detail. 45 These several joints will be considered with particular reference to the self-supporting, open-ended, building units or wall grids, above described.

Wall grid members 10 of any suitable configuration and design adapted to support any given load are supported on the floor members 40 and monolithically bonded thereto, a suitable channel member 160 being interposed therebetween. This member includes a wall grid re- 55

ceiving portion 161 with which is associated a base moulding member 162. A combined grid channel and base-board are suitably secured, as by crimping together at 163, and are preliminarily positioned on top of the floor grids 40, being secured thereto by any suitable plastic embedment, although, of course, any mechanical means such as bolts and nuts and tie wires may be used, if desired. The wall grids 10 are inserted in the channel members, the latter having been first filled with suitable material, while still plastic, indicated generally at 154. This latter serves as an embedment for the grid members in addition to the locking together of the grids by the improved key members shown and described above. The base moulding is provided with a plasterer's screed 164, which is directed downwardly to form an apron 165 which forms a substantially closed channel 166 with the other parts of the moulding. When the combined grid channel and base moulding is filled with cement or other plastic, the inverted chamber 166 acts as an air chamber or reservoir, and prevents the plastic material from rising therein. The screed 164 serves to support the plastic coat as well as being a guide for the thickness of the coat. It will be observed that there is no continuity between the plastic embedment and the wall coating. This condition serves to prevent the access of absorbed material from the exterior of the building in and through the plastic embedment to the wall coating. This break in continuity of plastic material afforded by the member 162, and more particularly by the intermediacy of the apron portion 165 and the air chamber 166, as above intimated, saves the plastic coatings 103 and 104 from deleterious action of absorbed moisture and permits the fabrication of a completely monolithically surfaced and bonded house without introducing the noxious feature of damp interior walls and rooms normally met with when walls are made of solid concrete or other plastic material, which exercises a capillary attraction for moisture, whether atmospheric or derived from moist earth as in tropical countries.

The floor grid units may be adapted to form concrete beam members monolithically bonded to the floor coverings and supporting walls and columns or partitions by cutting back the top portions 11 from a member 40 a suitable distance to provide an apron portion 170, which is bent downwardly into engagement with the bottom member, and secured thereto in any suitable manner as by means of tie wires 171. When positioned in place and a suitable concrete mix poured therein, it will be noted that a solid segment of concrete, as indicated at 153, is formed in the end portion and is integrally bonded with the mass of concrete indicated at 152 and 154, as well as with the subjacent plastic coatings 103 and 104.

Where wooden floors or the like are desired, suitable supports 172 of wood or other suitable material are embedded in the concrete 45 to a suitable depth, and floor members 47 also of wood or any desired material are laid thereon and fastened thereto, an air space 48 being provided to prevent warping of the floor members.

The base moulding, designated generally by the numeral 162, is set in place being embedded in the concrete mass, and is in turn filled with any suitable aggregate of the types previously described. These members and their associated

parts are shown in detail in Figures 6 to 10. Referring more particularly to Figure 7, the base moulding comprises a bottom channel portion 180 bent over at one edge to form an inverted U-shape member 163, the shorter leg of which is adapted to receive any of wall channel members 160, 190 and 191. The longest side of the U is provided at its lower portion with apertures 183 as is the portion of the member, and is extended above the apertures to form a base board 162, which may be given any desired configuration for ornamental purposes. The plasterer's screed is formed integrally therewith.

Suitably associated with the base moulding is an exterior wall channel 160. This member comprises a bottom portion suitably apertured and provided with a short upstanding portion 184 adapted to engage or fit into member 163, previously described.

The other leg 161 of the member is apertured in the same manner as the base portion, and is provided at its upper end with an out-turned flanged portion 185. The base moulding and exterior wall channel may be fitted together and placed in position on top of the supporting concrete mass and floor members, thus having the combination of a good metallic and structural concrete support, together with the improved bonding effect of the monolithic mass, previously described.

Where partition floors are being constructed, a plurality of base moulding members are joined by a partition channel 191 having upstanding flanges of equal height. This combination of parts is supported on the floor members and their associated fillings in the same manner as the wall moulds and are provided with like plastic fillings.

Referring now to Figures 5 to 10, the details of an exterior wall and floor joint will be described. This construction comprises a combination wall grid cap, as shown in Figure 8, and designated generally by the numeral 195. This member includes a lower inverted channel member having a flat medium portion 196, and depending sides 197, provided with usual apertures 183. The members 197 are provided with upturned flanges 198, which are adapted to serve the joint purpose of a picture moulding support for a picture moulding 199, and also as a plasterer's guide for determining the depth of the initial coat of plastic. The upper portion of the combination grid cap member is formed of a similar channel shaped member having a base portion 200 and side portions 201 and 202. The upper and lower portions of member 195 may be secured together by welding or riveting. Members 201 and 202 are provided with usual apertures 193, and member 202 is provided at its upper edge with a laterally extending flange 203, which also serves as a support for superposed floor members. Member 201 is provided with an inwardly displaced section 204, and is flanged outwardly at its upper portion to form a clip flange 205, which is adapted to engage the tongue 206 of a suitable tie-in member 207. This member, in addition to the tongue portion is provided with a body portion 208 having an intermediate section 209 provided with tongues 210, which are adapted to receive flanges of exterior wall clip channel 190. Member 207 is suitably apertured to permit the free flow of monolithic bond material therethrough. At its upper end the member is provided with a flange 185. It will be noted that the upper section of member 207 in combination with members 190 and 162 forms a wall grid receiving

channel, permitting a desired continuity of construction. The picture moulding as shown in Figure 5, and designated by the numeral 199, is made from sheet metal and is provided with a 5 clip channel portion 213, which is adapted to engage into member 198 of the wall caps and be supported thereby. The members provided with outstanding portions 211 and 212 are adapted to serve as plasterer's guide for the final plastic coat. 10 A depending tongue or flange 214 is provided at the bottom of the moulding member, and is adapted to be anchored by the applied coat of plastic, thus preventing the picture moulding from being moved out of place.

15 Referring now to Figure 11, there is shown a detail of an eave and gable construction showing the manner of assembling the several parts to unite angularly disposed structures to the side walls. In this construction there is shown a grid 20 cap member designated generally by the numeral 195 and a superposed floor grid member 40, which, as previously intimated, may be of any suitable dimensions.

25 The roof members, designated generally by the numeral 216, are secured to the roof connection member 218 by means of hook bolts 217 having hook portions 219 adapted to receive a rod 220 which is inserted in a grooved portion 221 of member 218 and spot welded thereto. The hook 30 bolts are provided with threaded ends 222 which are associated with suitable nuts 223. It will now be appreciated that the member 220 serves as a fulcrum for member 217 about which the latter is adapted to rotate on hook 219, thus enabling any roof angle to be secured. This hinge-like construction permits the construction herein described to be used in roof members of a wide variety of types and in a wide variety of 35 designs, varying from the sharply pitched roofs of extreme northern latitudes to the flat roofs common in tropical countries.

40 Where the roof members 216 are of the grid type herein disclosed, this invention comprehends the use of an improved facia plate channel designated generally as 224. These members include 45 a drip cap 225, which is adapted to direct water flowing thereover into a suitable gutter 226. Member 222 is provided further with portions 227 bent inwardly toward each other and side portions 228 suitably apertured, the portions 228 being adapted to slip over and engage a roof member and be secured thereto by means of standard bolt and nut construction 229. These members may have any suitable depth, which can 50 be varied to suit the needs of any installation, and may be provided further with stiffening flanges. A gutter 226 is supported from members 229 by means of woven wire hangers 230.

55 As shown in Fig. 12 the members 216 are abutted against each other and are suitably supported on a ridge angle 231, which is suitably apertured, and are secured thereto by suitable bolt and nut construction 232. Members 231, being of machine material may be bent to any 60 suitable angle. The ends of members 216 are abutted at the ridge with a cover piece of expanded material 233 which is laid thereagainst and serves to retain the plaster material 234 which 65 is led through the grids. The underside of the grids are plastered in the ordinary manner with any suitable plaster, or they may be gunited or otherwise treated. In the upper plastic a sheet 70 75 of suitable waterproof material such as any suitable roofing felt or roofing paper may be

applied. Over this waterproof covering is applied a suitable waterproof plastic 236 which may be of suitable color or which may be used or blocked off to imitate shingles or the plaster may serve as an imitation of tiles, shingles or other composition shingles or equivalent materials. Where the wooden or shingle finish is desired, wooden nail strips or sleepers may be disposed in the plaster at suitable intervals and the wooden shingles or wooden clapboards nailed thereto. 5

10 Having now particularly described and ascertained the nature of my said invention and in what manner the same is to be performed, I declare that what I claim is:

1. In a building structure of the class described, 15 an improved wall and floor joint comprising a wall section, a floor grid supported on said section, the top of said floor grid being folded back a distance equal to the depth of the grid and attached to the bottom of the grid to form a channel section, further wall sections superposed on 20 and across said floor sections and a common cementitious bond between the said wall sections and the intermediate floor sections.

2. In a building construction of the class described, 25 an improved wall and floor joint comprising self-supporting wall sections, means mounted on the wall sections for engaging and supporting superposed floor sections and to form continuous beam members and channel sections 30 therewith, separate wall sections mounted on the said floor sections, the said wall sections and floor sections being mechanically connected and interlocked, and a common cementitious bond between the said wall sections and interposed 35 floor sections and associated parts.

3. An improved wall joint assembly for building construction formed of self-supporting structural grid units, comprising wall sections, composite wall grid cap and channel members superposed on and over said sections, floor grids supported on said composite members, tie-in members 40 clipped to the channel members of the said composite wall grid cap and channel members, separate channel supports having lateral, 45 standing flanges clipped on to the tie-in plates by one of the said flanges, the other flanges of said channel members being clipped by and adapted to support combination mould members and plasterer's screeds, wall grid members mounted in the 50 last said channel members and between the upper portion of the tie-in plates and the combination mouldings and plasterer's screeds, cementitious plastic disposed in the channel portion of the composite wall grid cap and channel members and extending through the end of the superposed floor grids, forming a beam section therewith, a cementitious plastic disposed in the bottom 55 of the upper wall grid members and integral with the cementitious beam members, a coat of plastic disposed exteriorly of the several wall grid cap and channel members and associated tie-in plates on one side of the construction and keyed thereto by flange portions thereof, and interior plastic coats disposed on the interior of 60 said composite construction and maintained in alignment by the said plasterer's screeds.

4. An improved skeleton structure for wall joint assemblies for building construction formed of self-supporting structural grid units, including, 65 in combination, self-supporting wall sections having spaced panel members spaced and supported by end keying members, composite wall grid cap and channel members fitting on and over said sections, floor grids supported on said composite 70 75

- members, tie-in members clipped to the channel members of the said composite wall grid cap and channel members, separate channel supports comprising plate members having lateral upper standing flanges clipped on to the tie-in plates by one of the flanges, the other flanges of said channel members being clipped by and adapted to support combination mold members and plasterer's screeds; wall grid members mounted in the last said channel members and between the upper portion of the tie-in plates and combination moldings and plasterer's screeds, all of the said members being perforated and adapted to receive cementitious plastic in a substantially monolithic condition.
5. An improved tie-in member for self-supporting wall grid constructions and associated channel sections comprising a plate member having a horizontal clip flange formed at the bottom thereof, an intermediate bellied horizontal rib formed in the plate and provided with tongue forming clip fingers, and a flange formed at the upper edge of the said plate and parallel with the aforesaid bottom clip flange.
20. 6. An improved structural member forming a combination base moulding and plasterer's screed comprising a bottom portion having an upstanding clip flange formed on one side thereof, the other side being upwardly extended to form a base moulding and a plasterer's screed at the top of said moulding section, the free edge of the screed section being in substantial alignment with the clip member of the bottom section.
25. 7. A combination wall grid cap and grid channel member comprising a bottom U-shaped section having upwardly extending flanges at the free ends thereof, a separate U-shaped section superposed on and secured to the bottom U-shaped section, said upper section having flanges formed at the top edge portions thereof, the said top flanges being adapted to serve as guides and supports for superposed floor grid members.
30. 8. A combination wall grid cap and grid channel member comprising a bottom inverted U-shaped section having upwardly extending flanges at the free ends thereof, a separate U-shaped section superposed on and secured to the bottom U-shaped section, said upper section having flanges, at least one of the said flanges being reversely bent to form a clip flange, the said top flanges being adapted to serve as guides and supports for superposed floor grid members.
35. 9. In a building construction of the class described, an improved inner wall and floor joint permanent form comprising, a wall section, means mounted on the wall section for engaging and supporting a plurality of abutted and superposed floor sections extending laterally from the wall section and having their respective upper portions retracted inwardly on themselves where-
5. by to form a continuous beam member and channel section therewith, and a separate wall section mounted on the abutted floor sections at their point of juncture, the said wall sections and floor sections being mechanically connected and interlocked.
10. In a building construction of the class described, an improved inner wall and floor joint comprising, self-supporting wall sections, means mounted on the wall sections for engaging and supporting superposed, abutted floor sections having retracted top members adapted to form continuous beam members and channel sections therewith, separate wall sections mounted on said floor sections, said wall sections and floor sections being mechanically connected and interlocked, and a common cementitious bond between the said wall sections and interposed floor sections and associated parts.
15. 11. An improved wall and roof joint, comprising a wall member, a wall grid cap mounted on said wall member, a floor grid mounted on the said wall grid cap and forming a channel member therewith, a facia plate clipped on to the wall grid cap member, the said facia plate being provided with an upper hooked portion having a lateral extending flange, a roof member supported at an angle on the said hooked portion of the facia plate, a bolt inserted in the hooked portion of the facia plate and engaged by bolt members, the said bolt members being secured to roof grid members, a common cementitious bond between the said wall members, superposed flooring and associated roof members, and a waterproof coating on the outer surface of the said roofing.
20. 12. Improved grid-receiving and supporting channel members, comprising a perforated bottom section with flanges on either side and defining a channel with the said bottom, at least one of said flanges being extended upwardly and perforated, and both of said flanges being adapted to act as supporting members for superposed structural unit building members.
25. 13. A building member as set forth in claim 12 and characterized by flanges of unequal height, the longer of said flanges being perforated and provided with an outwardly extending stiffening and supporting flange.
30. 14. In a building construction as set forth in claim 4 the improvements comprising a channel member in which the flanges are of substantially equal height and perforated, the exterior or outer flange being itself provided at its top with a clipped flange portion forming a stiffening bead and the other said flange being provided in its turn, with an outwardly extending plain stiffening edge or flange.
